US00D786097S

(12) **United States Design Patent** (10) **Patent No.:** **US D786,097 S**
(45) **Date of Patent:** **** May 9, 2017**

(54) **THERMOMETER**

(71) Applicant: **Jacob Alan Stanton**, Chicago, IL (US)

(72) Inventor: **Jacob Alan Stanton**, Chicago, IL (US)

(73) Assignee: **Weber-Stephen Products LLC**,
Palatine, IL (US)

(**) Term: **15 Years**

(21) Appl. No.: **29/556,181**

(22) Filed: **Feb. 29, 2016**

(51) LOC (10) Cl. **10-04**

(52) U.S. Cl.

USPC **D10/60; D10/57**

(58) **Field of Classification Search**

USPC D10/57, 60

CPC G01K 1/083; G01K 1/18; G01K 13/002

See application file for complete search history.

(57) **CLAIM**

The ornamental design for a thermometer, as shown and described.

DESCRIPTION

FIG. 1 is a front perspective view of a thermometer of the present invention;

FIG. 2 is a back perspective view of the thermometer of the present invention;

FIG. 3 is a top view of the thermometer of the present invention;

FIG. 4 is a front view of the thermometer of the present invention;

FIG. 5 is a left side view of the thermometer of the present invention;

FIG. 6 is a back view of the thermometer of the present invention;

FIG. 7 is a right side view of the thermometer of the present invention; and,

FIG. 8 is a bottom view of the thermometer of the present invention.

The broken lines shown in the Figures are for illustration purposes only and form no part of the claimed design.
